CLAIM

The ornamental design for a linear surgical stapler, as shown and described.

DESCRIPTION

FIG. 1 is a perspective view of a linear surgical stapler, showing our new design;

FIG. 2 is a front elevational view of the linear surgical stapler of FIG. 1;

FIG. 3 is a rear elevational view of the linear surgical stapler of FIG. 1;

FIG. 4 is a left elevational view of the linear surgical stapler of FIG. 1;

FIG. 5 is a right elevational view of the linear surgical stapler of FIG. 1;

FIG. 6 is a top plan view of the linear surgical stapler of FIG. 1; and,

FIG. 7 is a bottom plan view of the linear surgical stapler of FIG. 1.

The broken lines in the drawings depict portions of the linear surgical stapler that form no part of the claimed design.

1 Claim, 4 Drawing Sheets
